HACK SAW FRAME

Filed Sept. 20, 1944

UNITED STATES PATENT OFFICE

2,538,480

HACKSAW FRAME

Clifford Sprague, Wilmar, Calif.

Application September 20, 1944, Serial No. 554,955

3 Claims. (Cl. 145—31)

1

My invention relates to hacksaw frames, and among the objects of my invention are:

First, to provide a hacksaw frame wherein the spacing between the hacksaw blade and back bar of the frame may be readily and quickly varied.

Second, to provide a hacksaw frame which incorporates novel end fittings for the hacksaw blade which are so arranged that even when the blade is loosened to permit adjustment of its angular relation with the frame or its space from the back bar, the blade cannot fall out of the end fittings; however, at least one of the end fittings being adapted to move onto the back bar of the frame to permit, when in such position, ready insertion or removal of the blade.

Third, to provide a hacksaw frame which incorporates a novel handle construction wherein the connection between the handle and the frame is in alignment with the hacksaw blade, the handle being so arranged that it may be placed in any angular relation with the U-bracket which joins the ends of the hacksaw blade.

Fourth, to provide a hacksaw frame which, by reason of the angular and spacing adjustment of the blade and angular adjustment of the handle, permits use of the hacksaw in awkward places where a conventional hacksaw could not be used. With the above and other objects in view as may appear hereinafter, reference is directed to the accompanying drawings, in which:

Fig. 1 is a fragmentary side elevational view of the hacksaw frame showing by dotted lines an adjusted position of the hacksaw blade, and by other dotted lines the position of one of the end fittings when removing or inserting a hacksaw blade.

Fig. 2 is an enlarged fragmentary sectional view through 2—2 of Figure 1 showing the connection between one of the end fittings and the hacksaw blade, and illustrating the manner in which the blade is retained and the manner in which it is inserted or removed when the end fitting is in the proper position.

Figure 2A is a sectional view through 2A—2A of Figure 1 showing in elevation one of the end fittings on the strut of the hacksaw frame in the position assumed when inserting or removing a hacksaw blade, the hacksaw blade being shown tilted about its longitudinal axis for this purpose.

Fig. 3 is a transverse sectional view of the end fitting taken through 3—3 of Fig. 2.

Fig. 4 is a fragmentary side elevational view of a modified form of hacksaw frame wherein the handle is attached on an axis aligning with the hacksaw blade.

2

Fig. 5 is an enlarged sectional view thereof taken through 5—5 of Fig. 4.

The hacksaw frame includes a main strut 1 of channel-form, which is attached at its rear end 5 to a handle frame 2. The handle frame is U-shaped in form and one leg thereof is encased in a molded handle 3. The main strut is secured to the cross portion 4 and the remaining leg 5 of the handle frame 2. The leg 5 extends at right angles to the main strut.

The main strut receives an adjustable strut 6 which is L-shaped, one leg fitting within the main strut and the other leg 7 disposed at right angles thereto. The manner in which the main strut and adjustable struts are connected is conventional, and therefore not shown in detail.

The legs 5 and 7 carry slide members 8 and 9. The slide members are in the form of bars having transverse slots 10 which receive the legs 5 and 7. The extremities of the legs may be upset or staked as indicated by 11 to retain the slide members thereon. The slide members 8 and 9 are substantially the same except that the slide member 8 which fits the rear leg 5, is longer than the slide member 9 and also its slot is longer to permit limited longitudinal movement relative to the leg 5. A thumb screw 12 is threaded into the rear end of the slide member 8 and enters the slot 10 to engage the leg 5.

Each slide member is provided with a socket 13 which receives a stem 14. The stem 14 is provided with a head 15 which is held within the socket 13 by a shoulder 16 formed by rolling inward the mouth of the socket 13. Each head 15 is capable of limited axial movement in its socket 13. Slots 17 are provided in the periphery of each head 15. These slots are preferably located 90° apart. At a suitable point in the periphery of the socket 13 a stake 18 is formed, providing an internal projection adapted to fit any of the slots 17 and prevent rotation of the stem 14. The stake engages the slots when the head 15 is moved toward the shoulder 16 and disengages the slots so that the stem 14 may be rotated when the head is moved into the socket 13.

The extended end of each stem 14 is provided with a notch 19 cut therein along the longitudinal axis of the stem. The axial end of each notch 19 is undercut as indicated by 20. Outwardly from the undercut a pin 21 extends into the space formed by the notch. Each pin 21 is disposed in converging relation with the slope of the undercut 20.

The proportions of the notch 19, undercut 20, and the pin 21, which together form a hook

element, are such that a conventional hacksaw blade **B** can only be inserted or removed when the plane of the hacksaw blade is in angular relation (approximately 45°) with the axis of the stem, as shown in Figure 2A. However, this angular relation can only be assumed when the slide member is on the strut **6** and its longitudinal axis is in substantial angular relation, that is, the angular position of the hacksaw blade shown by broken lines in Figure 1.

When the slide is on the leg **7** this necessary angular relation cannot be obtained and, hence, even though the blade be loosened, it cannot fall free.

This is of primary practical importance for it enables one to adjust with ease the angular relation of the blade with respect to the hacksaw frame, or to move the slide members and blade along the legs **5** and **7** for adjusting the spacial relation between the blade and the main strut **1** of the frame. Not only may the blade be moved in a parallel plane, but one slide may be moved further than the other to dispose the blade in angular relation with the main strut. This adjustment enables the hacksaw to be used in cramped quarters where a conventional hacksaw could not be employed. By way of example, this adjustment of the hacksaw blade enables the hacksaw to be used for the purpose of severing boiler tubes where the clearance between the tubes is less than the extended distance between the hacksaw blade and the back of the hacksaw. The hacksaw may be slipped into place with the blade, for example, in its dotted line position, and as the tube is cut the hacksaw blade may be adjusted outwardly.

When the slides are loosened and the slide **9** is in the dotted line position shown in Figure 1; that is the position shown in Figure 2A, the blade may be rotated or twisted about its longitudinal axis while the other end remains attached to the stem of the slide **8**. This movement about the longitudinal axis of the hacksaw blade may be continued until the blade is tilted sufficiently to clear the pin **21** as shown best in Figure 2A. Once this end of the blade is unhooked from slide **9** the blade may be tilted about either its longitudinal axis or transverse axis until free to disengage the stem of the slide **8**. Thus, to install the blade in the hacksaw frame the blade is first secured to the stem of the slide **8** and then to the stem of the slide **9**, and to remove the blade, the steps are reversed.

It should be observed that when the slide **8** is loosened sufficiently, its stem may move into the slide to disengage stake lug **18** and slots **17**, thereby to permit free rotation of the hacksaw blade. The connection between the blade and the stem **14** is sufficiently loose that the longitudinal axes of the stem and blade may be in nominal angular relation without interfering with rotation of the blade.

Reference is now directed to Figs. 4 and 5, wherein a special handle adapted for use in conjunction with the slide member **8** is employed. In this construction a single piece U-frame **31** may be substituted for the main and adjustable struts **1** and **6**. A tapered ferrule **32** provided with a socket **33** fits over the slide member **8**. The extended end of the ferrule forms a tapered mandrel **34** which receives a stem **35**. The stem **35** includes a threaded portion **36** which extends into the socket **33** and is threaded into the end of the slide member **8** to engage a leg of the U-frame **31**. The stem **35** also extends outwardly

from the mandrel **34**, and is provided with a second threaded portion **37** which receives a nut **38** for securing the stem to the ferrule **32**. A handle **39** which may be formed of a molded plastic, is provided with a handle arm **40** of metal extending therefrom and provided with a tapered socket **41** which fits over the tapered mandrel **34**. The axial extremity of the handle arm **40** and a shoulder formed at the base of the tapered mandrel **34**, may have complementary serrations **42** so that when the handle arm is fitted onto the mandrel it may be secured against rotation. A hole is provided axially through the handle arm **40** to receive the second threaded portion **37**, and a knurled nut **43** is provided for adjustably securing the handle arm to the ferrule **32**.

With this arrangement the handle, arm, and ferrule, may be rotated bodily as a unit to draw the slide member **8** laterally across the leg of the U-frame until the blade is sufficiently tightened. Thereupon the knurled nut **43** may be loosened and the handle turned until in the desired angular relation (normally in the plane of the U-frame) and the knurled nut re-tightened. In this construction as in the previously described structure, the hacksaw blade cannot be removed from the stems **14** until one or the other slide members is moved to the strut or cross portion of the U-frame.

The extremity of the ferrule is adapted to bear against the edge of the leg **5** on opposite sides of the shank to restrain the handle from rotation once the blade is tightened.

Many other embodiments of this invention may be resorted to without departing from the spirit of the invention.

I claim:

1. A hacksaw construction for a hacksaw blade having perforated ends and comprising: a pair of slides, a hook member carried by each slide, each hook member having a longitudinal axis and including a laterally extending pin and a shoulder confronting said pin, the face of said shoulder and the axis of said pin converging, whereby the perforated end of a hacksaw blade must be disposed at a substantial angle relative to the hook member to fit over said pin and under said shoulder; a frame for said slides including a track for one of said slides, said track having a bend whereby the hook member of said one slide may be moved between a position in which the longitudinal axes of said hook members are coaxial, thereby to limit angular movement of said hacksaw blade and retain said hacksaw blade thereon, and a position in which the longitudinal axes of said hook members are angularly related thereby to permit connection and disconnection between said hacksaw blade and said hook members.

2. A hacksaw construction for a hacksaw blade having perforated ends and comprising: a pair of slides, a hook member carried by each slide, each hook member having a longitudinal axis and including a laterally extending pin and a shoulder confronting said pin, the face of said shoulder and the axis of said pin converging, whereby the perforated end of a hacksaw blade must be disposed at a substantial angle relative to the hook member to fit over said pin and under said shoulder; a frame for said slides including a track for one of said slides, said track having a bend whereby the hook member of said one slide may be moved between a position in which the longitudinal axes of said hook members are coaxial, thereby to limit angular movement

of said hacksaw blade and retain said hacksaw blade thereon, and a position in which the longitudinal axes of said hook members are angularly related thereby to permit connection and disconnection between said hacksaw blade and said hook members; and a swivel connection between each hook member and its slide permitting rotation of said hook member and limited axial movement of said hook member relative to its slide.

3. A hacksaw construction for a hacksaw blade having perforated ends and comprising: a pair of slides, a hook member carried by each slide, each hook member having a longitudinal axis and including a laterally extending pin and a shoulder confronting said pin, the face of said shoulder and the axis of said pin converging, whereby the perforated end of a hacksaw blade must be disposed at a substantial angle relative to the hook member to fit over said pin and under said shoulder; a frame for said slides including a track for one of said slides, said track having a bend whereby the hook member of said one slide may be moved between a position in which the longitudinal axes of said hook members are coaxial, thereby to limit angular movement of said hacksaw blade and retain said

5 hacksaw blade thereon, and a position in which the longitudinal axes of said hook members are angularly related thereby to permit connection and disconnection between said hacksaw blade and said hook members; a swivel connection between each hook member and its slide permitting rotation of said hook member and limited axial movement of said hook member relative to its slide; and interlocking elements incorporating 10 each hook member and its slide for positioning said hook member in predetermined angular relation with said slide.
